UNITED STATES PATENT OFFICE.

ROBERT H. HASSSLER, OF INDIANAPOLIS, INDIANA.

VOLUTE-SPRING-EQUIPPED RADIUS-ROD.

1,165,405.

Specification of Letters Patent.

Patented Dec. 28, 1915.

Application filed June 8, 1915. Serial No. 32,917.

To all whom it may concern:

Be it known that I, ROBERT H. HASSSLER, a citizen of the United States, residing at Indianapolis, in the county of Marion and 5 State of Indiana, have invented certain new and useful Improvements in Volute-Spring-Equipped Radius-Rods, of which the following is a specification.

The object of this invention is to connect the 10 radius rods of motor-vehicles to the frame and axles through the agency of volute springs one of which is placed at each place of attachment of the rods to said frame and axles whereby the stress delivered longitudinally of the rod will be delivered radially of the volutes causing the resistance of their convolutions to act cumulatively in opposition.

The object also is to yieldingly resist 20 torsional and lateral stresses delivered through the rod.

Another object is to accomplish the above 25 functions with mechanism that is free from frictional parts. Frictional or sliding parts after prolonged usage become loose and rattle. In my present invention the advantages of longitudinal and torsional resiliency are secured and at the same time the 30 disadvantages of any sliding parts are avoided.

I accomplish the above and other objects which will hereinafter appear by the mechanism illustrated in the accompanying drawings, in which—

35 Figure 1 is a side elevation of an end of a front automobile axle with my invention applied in vertical section and showing some of the volute convolutions compressed. Fig. 2 is a top plan view of same. Fig. 3 is a 40 section on the line 3—3 of Fig. 1 showing the spring-casing broken away in part, and Fig. 4 shows the application of my invention to the frame of the machine, the latter being in vertical section and the spring-casing and spring sectioned in part.

Like characters of reference indicate like parts throughout the several views of the drawings.

50 Referring to Figs. 1, 2 and 3, 5 is the axle and 6 the spring-perch, to a portion of which above the axle one end of a radius-rod 7, is usually attached, but in my assembly I prefer to attach to the perch-bolt where it extends below the axle. A volute spring 8 is held by the perch-bolt which 55 passes through the inner coil of the spring,

and through a pair of washers 9 and 10, between which washers the spring is impinged by a castellated nut 12 on the threaded end of the bolt. The adjacent faces of the washers are preferably beveled to avoid interference between them and the spring within the greater but still defined limits which the washers are intended to afford. The spring 8 is supported by an annular casing 13, 60 which has an inside channel 14 in which the outer coil of the spring is seated. A socket extension on one side receives an end of the radius-rod 7, to which rod the socket which is split longitudinally, is rigidly clamped 70 by bolts 15.

Where the attachment is made to the frame, as for the inner ends of the radius-rods, a bolt 6' is seated in a specially formed hanger 15', which is bolted to the frame in 75 the manner shown in Fig. 4. Other adaptations of the bolt-support will be made for fastening to the rear axle which is usually tubular and through which the bolt cannot pass on account of its contained mechanism, 80 and to other support-forms, as circumstances require, and as will suggest themselves to the skilled mechanic, and without departing from the spirit of this invention.

In the operation of my device, any pressure 85 from the radius-rod whether delivered longitudinally or laterally from the latter, but radially of the volute spring, will press the first convolution in the line of stress toward the next convolution of the spring and 90 into contact with it if the force is great enough, whereupon the second convolution will add its resistance, and so on cumulatively until the elasticity of all of the convolutions between the outer casing and the 95 central bolt has been utilized. The volute suspension between the casing on the radius-rod and the central bolt affords elastic resistance to stresses to or from the radius-rod in all other directions. 100

Having thus fully described my invention, what I claim as new and wish to secure by Letters Patent of the United States, is—

1. The combination with a radius-rod, of 105 means having a limited elastic action in all directions by the operation of a single spring having convolutions approximately in the same plane as the rod for attaching and supporting one or both ends of the rod. 110
2. The combination with vehicle parts, of a radius-rod and means for connecting both

ends of the rod with said vehicle parts, one or both of said connecting means comprising a volute spring having convolutions in substantially the same plane as the rod 5 which afford an elastic limited movement of the rod-end relative to the vehicle parts with which the end is connected.

3. The combination with vehicle parts and a radius-rod connecting said parts, of 10 means for attaching the rod to said parts comprising a holder, a volute spring within the holder to which the rod is attached radially of the spring.

4. The combination with vehicle parts 15 and a radius-rod bracing them, of resilient connections at one or both ends of the rod comprising an annular casing and a volute spring within the casing radially of which stresses also directed longitudinally of the 20 rod are delivered to and from the rod.

5. The combination with vehicle parts and a radius-rod bracing them, of resilient 25 connections at one or both ends of the rod comprising an annular casing, a volute spring seated therein and lying approximately in the same plane as the rod, and a bolt supported by a vehicle part and fastened to the inner convolution of the spring.

6. The combination with vehicle parts 30 and a radius-rod bracing them, of resilient

connections at one or both ends of the rod comprising an annular casing, a volute spring seated therein and lying approximately in the same plane as the rod, a bolt supported by a vehicle part and passing 35 through the inner convolution of the spring, and a pair of washers on the bolt between and by which washers the position of the spring on the bolt is retained.

7. The combination with vehicle parts 40 and a radius-rod bracing them, of resilient connections at one or both ends of the rod comprising an annular internally channeled casing radially of which the rod is rigidly secured, a volute spring seated in the channel 45 of the casing, a bolt supported by a vehicle part and passing through the inner convolution of the spring, a pair of washers on the bolt between which the spring is held and means for holding the washers on 50 the bolt.

In witness whereof, I have hereunto set my hand and seal at Indianapolis, Indiana, this 31st day of May, A. D. one thousand nine hundred and fifteen.

ROBERT H. HASSSLER. [L. s.]
